PAGE 2

Fig. 2

Fig. 3

Fig. 4

Fig. 5

FIGURE 1 is a side elevational view of a dry foam carpet shampooing machine, showing my new design;
 FIGURE 2 is an elevational view of the opposite side thereof;

FIGURE 3 is a top plan view thereof;

FIGURE 4 is a front elevational view thereof; and

FIGURE 5 is a rear view thereof.

The electric cord is shown broken away in FIGURES 1 to 5 for convenience of illustration.

This is a continuation-in-part of design application Ser. No. D. 4,415, filed Oct. 24, 1966, and now abandoned.

I claim:

The ornamental design for a dry foam carpet shampooing machine, substantially as shown and described.
